Primary Examiner—Jeffrey Asch*Attorney, Agent, or Firm*—Perman & Green, LLP**[57]****CLAIM**

The ornamental design for a “communicator”, as shown and described.

DESCRIPTION

FIG. 1 is a perspective view of the bottom and inside of a communicator in an open position incorporating my new design;

FIG. 2 is a rear, bottom, left side perspective view of the communicator in FIG. 1 in a closed position thereof;

FIG. 3 is a front, bottom, right side perspective view of the communicator shown in FIG. 2 in a closed position thereof;

FIG. 4 is a front view thereof;

FIG. 5 is a rear view thereof;

FIG. 6 is a view showing the right side thereof;

FIG. 7 is a view showing the left side thereof;

FIG. 8 is a top view thereof;

FIG. 9 is a bottom view thereof; and,

FIG. 10 is a perspective view of the communicator in an open position from an opposite perspective as shown in FIG. 1 thereof.
